UNITED STATES PATENT OFFICE

EVERETT IRVING ROGERS, JR., OF PROVIDENCE, RHODE ISLAND

TOY BUILDING CONSTRUCTION

Application filed April 22, 1930. Serial No. 446,371.

This invention relates to elements for building toy or model structures, such as aeroplane fuselages, bridges and other objects.

5 My invention is particularly adapted for use for making various types of toy aeroplane fuselages for model aeroplanes. So far as I am aware I believe I am the first to construct a toy aeroplane fuselage of hollow 10 light metal tubing, such as aluminum.

My invention includes hollow members preferably tubing preferably provided with an inwardly projecting groove therein and preferably provided with two diametrically 15 opposed grooves of this type. The grooves not only assist in binding the various parts of my invention together but they also materially strengthen the tubing. I provide means to secure the pieces of tubing together 20 at angles to each other preferably substantially in the same plane comprising clip members each having a split tubular head adapted to surround one piece of tubing and attaching prongs projecting outwardly from 25 the edges of the split in said head having spaced lower portions of substantially hemi-tubular form registering within an end of a second piece of tubing abutting an inwardly projecting groove thereof to secure said 30 tubing to said clip against rotative movement thereon and preferably also inwardly inclined portions above said hemi-tubular portions. With this construction it is possible to secure the head of said clip member 35 to the first piece of tubing and by sliding said first piece of tubing within until it is brought to the desired angle with relation to the desired position of a second piece of tubing and indenting a portion of said head 40 within said groove to secure said head to said tubing against rotative movement thereon.

After the second piece of tubing has been inserted over the prongs it is possible to burnish or turn over the ends of said second 45 piece of tubing over the inclined portions of said prongs to secure said second piece of tubing to said clip against longitudinal movement thereon. By inserting the prongs into said second piece of tubing so as to have 50 the edges thereof abut the inwardly project-

ing groove thereon, it is obvious that said clip member is secured to said second piece of tubing against rotative movement therein by said groove. Objects of my invention therefore are to provide a toy or model building 55 construction including tubing and hollow members preferably clip members for attaching two pieces of said tubing together at angles to each other. With one type of clip the pieces of tubing are attached approximately at right angles to each other. If it is desired to attach said pieces of tubing at other than at right angles to each other the clip members are constructed so as to be pivotable. I also preferably construct the heads 60 of the clip member so that when attached it will be of slightly smaller periphery than that of the piece of tubing embraced, thereby to additionally squeeze said head around the tubing to bind it thereto and in attaching the second piece of tubing over the prongs to compress them so that the expansive action of the prongs will function additionally as a wedge to secure said second piece of tubing to said clip member. 70

A further object of my invention is to provide toy building elements which may be readily attached together at any desired angle by boys. In use the tubing is sold of a standard length, sawed off by the boy to any 80 desired length and the clip members are attached by the boy. The boy may burnish over the ends of the second piece of tubing over the inclined portion of the prongs with any simple tool and may similarly indent the 85 desired portions of the clip head within the tubing groove. While I preferably employ inwardly grooved round tubing, it is obvious that the clip members and hollow members may be of any desired shape so as to prevent relative turning movement between the 90 clips and hollow members.

These and such other objects of my invention as may hereinafter appear will be best 95 understood from a description of the accompanying drawings, which illustrate various embodiments thereof employing inwardly grooved tubing.

In the drawings, Fig. 1 is a perspective view 100

of an aeroplane fuselage constructed from the elements of my invention.

Figs. 2^a and 2^b are perspective views of different sized lengths of tubing which may be employed.

Fig. 3^a is an end elevation and Fig. 3^b a side elevation of a clip member adapted to attach two pieces of tubing of the same relative size together.

10 Fig. 4^a is an end elevation and Fig. 4^b a side elevation of a clip member suitable for attaching a smaller piece of tubing to a larger piece of tubing embraced by the head thereof.

15 Fig. 5^a is an end elevation, and 5^b a side elevation of a clip member adapted to attach a larger piece of tubing to a smaller piece of tubing embraced by the head thereof.

20 Fig. 6 is a perspective view illustrating the step of sliding the clip member over the first piece of tubing.

Fig. 7 is a perspective view showing a clip attached around the first piece of tubing and a second piece of tubing about to be inserted over the prongs of said clip.

25 Fig. 8 is a perspective view of the second piece of tubing inserted over the prongs of the clip member.

30 Fig. 9 is a perspective view showing how the head of the clip member may be indented within the groove in the first piece of tubing to secure said head to said first piece of tubing against rotative movement and how the ends of said second piece of tubing may be bent over the inclined portions of said prongs 35 to secure said second piece of tubing to said clip against longitudinal movement.

Fig. 10 is a cross sectional view taken along the line 10—10 of Fig. 8 showing how the prongs fit in between the grooves in the second piece of tubing.

40 Fig. 11 is a longitudinal sectional view taken along the line 11—11 of Fig. 9 also showing how the prongs fit in between the grooves and how a portion of the head may be 45 indented within the groove.

Fig. 12 is a plan view showing how portions of the head of the clip member may be indented within the groove in the first piece of tubing to secure it thereto against rotative 50 movement thereon.

Fig. 13 is a disassembled perspective view of an alternate form of clip member which may be employed when it is desired to attach two pieces of tubing together at an oblique 55 angle.

Fig. 14 is a perspective view of the clip member shown in Fig. 13 attached to two pieces of tubing.

In the drawings, wherein like characters 60 of reference indicate like parts throughout, 20^a and 20^b indicate standard lengths of tubing constructed in accordance with the principles of my invention, the tubing shown as 20^a in Fig. 2^a being of larger size than the tubing shown as 20^b in Fig. 2^b. Figs. 3^a

and 3^b indicate a clip member 22 of a type employed to attach the two pieces of tubing together at an angle to each other. In the embodiment shown in Fig. 3^a and Fig. 3^b the split head 24 of said clip is of substantial 70 ly the same periphery as the periphery of the spaced prongs 26 thereof for attaching two pieces of tubing of approximately the same size together. In the embodiment shown in Figs. 4^a, and 4^b the head 24 of the clip member 22 is of a larger periphery than the periphery of the split prongs 26 to attach a smaller piece of tubing to a larger piece of tubing. In the embodiment shown in Figs. 5^a and 5^b the split head 24 of the clip member 80 is of a smaller periphery than the periphery of the prongs 26 thereof to attach a larger piece of tubing to a smaller piece of tubing.

As shown in the drawings the pieces of tubing 20^a and 20^b are preferably provided with inwardly projecting grooves 28, preferably two as shown on diametrically opposite sides of said tubing for a purpose to be described. The clip member 22 is provided with the split tubular head adapted to surround a 90 piece of tubing 30 and attaching prongs projecting outwardly from the edges 32 of the split portion of said head having spaced lower portions 26 of substantially hemi-tubular form and of a size to compactly register with in an end of a second piece of tubing 34 preferably as shown in Fig. 10 between the inwardly projecting grooves 28 thereof to secure said tubing to said clip against rotative movement thereon. Said prongs are also 100 preferably provided for a purpose to be described with the inwardly inclined portions 36 above said hemi-tubular portions 26. Figs. 6—9 show the steps necessary to attach the second piece of tubing 34 to the first piece 105 of tubing 30. The prongs 26 of the clip 22 are split apart so that the clip 22 may be spread laterally so that the head 24 thereof may embrace the first piece of tubing 30 as shown in Fig. 6 after which when the prongs 110 are pinched together so as to compactly fit within the end 38 of the second piece of tubing 34. As shown in Fig. 7 the end 38 of said second piece of tubing 34 is placed opposite the prongs 26 and forced upwardly so that the prongs 26 may register within the end 38 of said second piece of tubing preferably between the grooves 28 thereof to secure said second piece of tubing against rotative movement on said clip. To secure the head 24 of 115 said clip member 22 against rotative movement on said first piece of tubing 30, portions 40 of the head thereof are indented inwardly within the groove 28. To secure the second piece of tubing 34 against longitudinal movement from said clip 22 the end portion 38 thereof is burnished over said inclined portions 32 as at 42 as shown in Fig. 9.

To make the action of the clip also a wedge action the split tubular head 24 of said clip is 120

- preferably when attached of slightly smaller periphery than said first piece of tubing 30 when the wedge prongs 26 are resiliently retained within said second piece of tubing.
- 5 The prongs 26 are also constructed to have a tendency to spread apart when inserted within the end 38, thus also resiliently tending to additionally bind said prongs 26 within said end 38 of said second piece of tubing 34.
- 10 In Figs. 13 and 14 I have shown a slightly different embodiment of my improved clip member including a pivotal portion in the prongs thereof. In this embodiment the head 24 is provided with the flat extensions 44 projecting outwardly from the edges 32 of the split in said head 24 and the prongs 26 are provided with an upwardly projecting flat portion 46 above the inclined portions 36 thereof insertable between the portions 44 projecting from said head 24 and pivotally attachable thereto by means of the pivot pin 48. Said head 24 and prongs 28 are pivotally attached together by said pivot pin so that when relatively tilted they will remain in a set position. This type of clip is employed when it is desired to attach the two pieces of tubing together at angles other than right angles for which the preferred type of clip shown in Figs. 3-10 is employed.
- 15 It is also apparent that if desired the members 30 and 34 may consist of hollow members of any configuration, preferably shaped so as to prevent the clip member from turning relative thereto, such as square, triangular, etc., and that as the shape of the hollow members are varied so must the shape of the clip members be correspondingly varied. It is apparent that the grooves 28 not only permit the locking action in a manner heretofore described, but that they also strengthen the tubing. I have shown in Fig. 1 an aeroplane fuselage built up of my improved pieces of tubing and clip members. Relatively long pieces of tubing 50 may be employed for the 20 longitudinal ribs of the fuselage and said longitudinal ribs may be joined together by the horizontal and vertical cross struts 52. In making up the fuselage body it is obvious that the cross struts 52 will be attached to the longitudinal ribs at substantially right angles to each other and therefore that the clip members 22 shown in Figs. 3-9 may be employed. The frame 54 for attaching the landing wheels thereto consists of V-shaped pieces of tubing depending from the lower longitudinal ribs and as it in this instance has the upper end of the V portion thereof attached to the lower longitudinal ribs 50 at an angle the type of clip member 22' shown 25 in Figs. 13 and 14 may be employed. The tubing and clip members may be constructed of any desired material, such as metal, celluloid, brass composition, etc., but in making model aeroplanes of a flying lightness I preferably use the hollow aluminum tubing

shown and so far as I am aware I am the first to provide an all metal toy aeroplane fuselage. I employ the word toy to include models of any sort, working models or otherwise.

70

It is thus obvious that I have provided a novel type of toy building construction which may be put together by a boy in relative easy fashion and which is particularly desirable for use in building toy aeroplane fuselages.

75

It is understood that my invention is not limited to the specific embodiments shown and that various deviations may be made therefrom without departing from the spirit and scope of the appended claims.

80

What I claim is:

1. In a toy building construction, in combination, a piece of relatively thin tubing having diametrically opposite inwardly pressed portions forming grooves in the outer surface and projections on the inner surface of the tube, a second piece of relatively thin tubing similarly shaped, and means for joining said pieces of tubing together at angles to each other in substantially the same plane, comprising a clip means having a split tubular head adapted to surround one piece of tubing having a portion thereof indented within an inwardly pressed portion thereof to retain said clip to said tubing against rotative movement thereon and a portion projecting downwardly therefrom and a prong member having a portion pivotally connected to said portion of said clip means, and attaching prongs projecting downwardly therefrom having spaced lower portions of substantially hemi-tubular form registering within an end of said second piece of tubing within the edges thereof abutting the inwardly pressed portions thereof to secure said tubing to said clip against rotative movement thereon, and inwardly inclined portions above said hemi-tubular portions, said second piece of tubing having a portion of an end thereof turned over said inclined portions of the clip to retain said second piece of tubing against longitudinal movement from said clip the tubular head of said clip being of slightly smaller periphery than that of said first piece of tubing when the wedge prongs thereof are resiliently retained within said second piece of tubing to assist in binding said clips to said pieces of tubing.

95

2. In a toy building construction, in combination, a piece of tubing, a second piece of tubing having an inwardly pressed portion forming a groove in the outer surface and a projection on the inner surface of the tube, and means for joining said pieces of tubing together at angles to each other in substantially the same plane, comprising a clip member having a tubular head adapted to surround one piece of tubing and attaching prongs projecting outwardly from said head having spaced lower portions of substantial-

100

115

120

125

130

ly hemi-tubular form registering within an end of said second piece of tubing abutting the inwardly projecting pressed portion thereof to secure said tubing to said clip 5 against rotative movement thereon.

3. In a toy building construction, in combination, a piece of relatively thin tubing having an inwardly pressed portion forming a groove in the outer surface and a projection on the inner surface of the tube, a second piece of relatively thin tubing similarly shaped, and means for joining said pieces of tubing together at right angles to each other in the same plane, comprising clip means 10 having a split tubular head adapted to surround one piece of tubing having a portion thereof indented within a pressed portion thereof to retain said clip to said tubing against rotative movement thereon and a portion projecting downwardly therefrom and a prong member having a portion pivotally connected to said portion of said clip means and attaching prongs projecting downwardly therefrom having spaced lower 25 portions of substantially hemi-tubular form registering within an end of said second piece of tubing abutting the edges of the inwardly projecting pressed portion thereof to secure said tubing to said clip against rotative movement thereon, and inwardly inclined portions above said hemi-tubular portions, said second piece of tubing having a portion of an end thereof turned over an inclined portion of the clip to retain said second piece of tubing against longitudinal movement from 30 said clip.

35 4. In a toy building construction, in combination, a piece of relatively thin tubing a second piece of relatively thin tubing having inwardly pressed portions forming grooves in the outer surface and projections on the inner surface of the tube, and means for joining said pieces of tubing together at angles to each other in the same plane, comprising a clip member having a split tubular head adapted to surround one piece of tubing, and attaching prongs projecting outwardly from the edges of the split in said head having spaced lower portions of 40 substantially hemi-tubular form registering within an end of said second piece of tubing abutting the edges of the inwardly projecting pressed portions thereof to secure said tubing to said clip against rotative movement thereon, the tubular head of said clip being of slightly smaller periphery than that of said first piece of tubing when the wedge prongs thereof are resiliently retained within said second piece of tubing to assist in binding said clips to said pieces of tubing.

45 5. In a toy building construction, in combination, a piece of relatively thin tubing having an inwardly pressed portion forming a groove in the outer surface and a projection on the inner surface of the tube, a second piece of relatively thin tubing similarly shaped, and means for joining said pieces of tubing together at angles to each other in the same plane, comprising a clip member having a split tubular head adapted to surround one piece of tubing having a portion thereof indented within a pressed portion thereof to retain said clip to said tubing against rotative movement thereon and inwardly inclined portions above said hemi-tubular portions, said second piece of tubing having a portion of an end thereof turned over an inclined portion of the clip to retain said second piece of tubing against longitudinal movement from said clip.

50 6. In a toy building construction, in combination, a piece of tubing, a second piece of tubing having an inwardly pressed portion forming a groove in the outer surface and a projection on the inner surface of the tube, and means for joining said pieces of tubing together at angles to each other in the same plane, comprising a clip member having a split tubular head adapted to surround one piece of tubing and attaching prongs projecting outwardly from the edges of the split in said head having spaced lower portions of substantially hemi-tubular form registering within an end of said second piece of tubing abutting the edges of the projections thereof to secure said tubing to said clip against rotative movement thereon and inwardly inclined portions above said hemi-tubular portions, said second piece of tubing having a portion of an end thereof turned over an inclined portion of the clip to retain said second piece of tubing against longitudinal movement from said clip.

55 7. In a toy building construction, in combination, a piece of relatively thin tubing, a second piece of relatively thin tubing having an inwardly pressed portion forming a groove in the outer surface and a projection on the inner surface of the tube, and means for joining said pieces of tubing together at angles to each other in the same plane, comprising a clip member having a split tubular head adapted to surround one piece of tubing having a portion thereof indented within a pressed portion thereof to retain said clip to said tubing against rotative movement thereon and attaching prongs projecting outwardly from the edges of the split in said head having spaced lower portions of substantially hemi-tubular form registering within an end of said second piece of tubing abutting the edges of the inwardly projecting pressed portion thereof to secure said tubing to said clip against rotative movement thereon and inwardly inclined portions above said hemi-tubular portions, said second piece of tubing having a portion of an end thereof turned over an inclined portion of the clip to retain said second piece of tubing against longitudinal movement from said clip.

60 8. In a toy building construction, in combination, a piece of relatively thin tubing, a second piece of relatively thin tubing having an inwardly pressed portion forming a groove in the outer surface and a projection on the inner surface of the tube, and means for joining said pieces of tubing together at angles to each other in the same plane, comprising a clip member having a split tubular head adapted to surround one piece of tubing and attaching prongs projecting outwardly from the edges of the split in said head having spaced lower portions of substantially hemi-tubular form registering within an end of said second piece of tubing abutting the edges of the projections thereof to secure said tubing to said clip against rotative movement thereon, the tubular head of said clip being of slightly smaller periphery than that of said first piece of tubing when the prongs thereof are resiliently retained within said second piece of tubing to assist in binding said clip to said piece of tubing.

65 9. In a toy building construction, in combination, a piece of tubing, a second piece of tubing having an inwardly pressed portion forming a groove in the outer surface and a projection on the inner surface of the tube, and means for joining said pieces of tubing together at angles to each other in the same plane, comprising a clip member having a split tubular head adapted to surround one piece of tubing and attaching prongs projecting outwardly from the edges of the split in said head having spaced lower portions of substantially hemi-tubular form registering within an end of said second piece of tubing abutting the edges of the projections thereof to secure said tubing to said clip against rotative movement thereon and inwardly inclined portions above said hemi-tubular portions, said second piece of tubing having a portion of an end thereof turned over an inclined portion of the clip to retain said second piece of tubing against longitudinal movement from said clip.

portion of an end thereof burnished over an inclined portion of the clip to retain said second piece of tubing against longitudinal movement from said clip.

8. In a toy building construction, in combination, a piece of tubing, a second piece of tubing having inwardly pressed portions forming grooves in the outer surface and projections on the inner surface of the tube, and means for joining said pieces of tubing together at right angles to each other in the same plane, comprising clip means having a split tubular head adapted to surround one piece of tubing and a portion projecting downwardly therefrom and a prong member having a portion pivotally connected to said portion of said clip means and attaching prongs projecting downwardly therefrom having spaced lower portions of substantially hemi-tubular form registering within an end of said second piece of tubing with the edges thereof abutting the edges of the inwardly projecting pressed portions thereof to secure said tubing to said clip against rotative movement thereon.

9. A toy building element, comprising clip means having a split tubular head adapted to surround a piece of tubing and a portion projecting downwardly therefrom and a prong member having a portion pivotally connected to said portion of said clip means and attaching prongs projecting downwardly therefrom having spaced lower portions of substantially hemi-tubular form and inwardly inclined portions above said hemi-tubular portions.

10. In a construction for toy airplanes, the combination of a piece of light tubing, a second piece of light tubing and clip means adapted to encircle one piece of tubing and having ends adapted to be inserted into the other piece of tubing for attaching the two pieces of tubing together, the ends of said clip being so constructed and arranged as throughout their length to engage the inner wall of the tube whereby said clip is frictionally held in said tube independently of additional clamping means.

11. In a construction for toy airplanes, the combination of a piece of light tubing, a second piece of light tubing and clip means adapted to encircle one piece of tubing and having ends adapted to be inserted into the other piece of tubing for attaching the two pieces of tubing together, the ends of said clip being so constructed and arranged as throughout their length to engage the inner wall of the tube whereby said clip is frictionally held in said tube independently of additional clamping means, the ends of the second piece of tubing being bent inwardly toward the clip means into engagement therewith.

12. In a construction for toy airplanes, the combination of a piece of longitudinally cor-

rugated light tubing, a second piece of longitudinally corrugated light tubing, and clip means adapted to encircle one piece of tubing and having its ends adapted to be inserted into the other piece of tubing with the ends of the clip cooperating with the corrugations of the other piece of tubing for holding the clip and tubing non-rotatively together.

In testimony whereof I affix my signature. EVERETT IRVING ROGERS, JR.
